UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

TANK-CAR.

1,336,439.

Specification of Letters Patent. Patented Apr. 13, 1920.

Original application filed November 5, 1914. Serial No. 870,413. Patent No. 1,199,816, dated October 3, 1916. Divided and this application filed March 29, 1916. Serial No. 87,523.

To all whom it may concern:

Be it known that I, ALLEN E. OSTRANDER, residing at Ridgewood, Bergen county, New Jersey, and being a citizen of the United States, have invented certain new and useful Improvements in Tank-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is a central vertical longitudinal 20 sectional view.

Fig. 2 is a central vertical transverse view of the tank and tank anchor at the left of the figure and an end elevational view at the right of the figure, the tank being broken to 25 permit showing details in larger section.

Fig. 3 is a vertical sectional view of a fragment of the tank and showing the tank dome in detail.

Fig. 4 is an enlarged fragmentary detail 30 view of part of the dome.

Fig. 5 is an isometric perspective showing part of the tank anchoring means herein-after described.

Fig. 6 is a similar view showing a filler 35 between the tank shells adapted to be connected to the outer shell and on which rests the inner tank shell.

Fig. 7 shows a detached detail of the manner of connecting sheets of the outer shell 40 near the top of the tank.

Fig. 8 illustrates in detail a fragment of the inner tank shell and how the insulation for the body portion of such shell is secured in position.

Fig. 9 illustrates in enlarged detail one of the binding wires and insulation-securing 45 clips herein-after described.

Fig. 10 is a detail plan view of part of the outer dome head, the dome cap and means so 50 locking the latter in closed position that

gaseous pressure relief must be obtained in the inner tank before said cap can be opened.

Fig. 11 is a fragmentary vertical section through a portion of the outer dome and an 55 elevation of part of the inner dome and dome cap and shows modified locking means for the cap; and

Fig. 12 is a fragmentary plan view of the outer dome head, the cap, the modified locking means and the pressure-relieving device. 60

This present application is divided from a parent case entitled "Tank car," filed by me November 5, 1914, Serial No. 870,413, this construction being shown and described in 65 said former application on which Letters Patent No. 1,199,816 issued Oct. 3, 1916.

The object of the present invention is to provide a tank adapted for use in tank cars, which tank is thoroughly insulated and is of 70 such construction that it may be readily assembled for use and it possesses an additional feature of advantage in that should it become necessary to repair the inner tank shell or the outer tank shell, the outer shell 75 may be removed from the inner shell with a minimum amount of labor, and the insulation may be removed so as to expose the inner shell which may be repaired and the parts reassembled or the inner shell may be 80 used as a tank of a tank car without the outer shell, if such outer shell has been removed.

The invention comprises two complete tanks, one of which is larger than the other, 85 the inner tank being removably mounted in position within the elements comprising the outer tank.

Another object of the invention is to provide means for insulating the interior tank 90 and for securing such insulation in position.

Other features of advantage are that the elements comprising the outer tank may be reassembled to form a tank independently 95 of the inner tank, if for any reason that should become desirable, and the invention also comprises means for anchoring the inner tank in position upon a car under-frame by means of devices common to the art associated with special attachments for 100

holding the two tank shells in proper position.

Referring specifically to the parts, 1 indicates the inner tank shell which is preferably provided with a cylindrical body portion and with convex heads 2 of the type commonly found in tank cars.

3 indicates the outer shell which is provided with concave heads 4. It will be noted that the tank shell 3 is of considerably greater length than is the tank shell 1 so that the flanges 5 of the concave head 4 may be riveted to said outer shell. It is understood that the flanges 6 of the inner head 2 are likewise riveted to the shell 1 of the inner tank.

Interposed between the outer and inner shells are secured sheets or blocks 10 and 11 of insulation which may be of any preferred type but as shown in Fig. 8 the sheets or blocks 10 and 11 are arranged so as to "break joints,"—that is, the joints between the sheets 10 are covered by the body portions of the sheets 11.

To secure the insulation 10—11 in position, binding wires 12 are wrapped about the inner tank shell 1 in the first instance, and secured, at convenient intervals apart, on such wires 12 are clips 13 which clips are provided with outstanding projections 14, which projections, as will be noted from Fig. 8, overlap contiguous sheets 10 of the insulation, and likewise lapped about the inner course of insulation 10 are binding wires 12, which have strung thereon similar clips with similar offset portions adapted to overlap the insulation sheets 11 thereby securing both inner and outer layers of insulation firmly in position upon the inner tank shell.

The inner tank shell is provided with a dome 15 and a dome head 16 secured thereto by rivets 17 which head telescopes with the dome 15.

The outer tank shell is provided with a dome 18, which dome 18 has outstanding flanges 19 secured to outstanding flanges 20 of its dome head 21 by vertical rivets 22 and intermediate the domes 15 and 18 insulation 25 is packed so as to thoroughly insulate such dome portions of the tank though it is to be noted that the insulation 25 is not of the block or sheet form.

The dome cap 26 is of peculiar construction and is filled with insulation 25. This cap is provided with screw threads so that it may be removably secured in position.

By referring to Fig. 3, it will be seen that the dome heads 16 and 21 are spaced apart, as are the shells 1 and 3. To maintain these heads and the domes 15 and 18 in their spaced relation, a pan member 28 is employed.

The pan 28 is preferably formed as an annular member having flanges at each end. One of the flanges is outwardly turned and

is secured to the dome head 21 by suitable means such as the rivets 30. The opening in the flange is threaded to coöperate with the threads formed on the cap 26. The other flange is inwardly turned, is riveted to inner dome head 16, and is also provided with an opening or aperture that registers with the aperture in the dome head 16. This flange is secured to the head by suitable means such as the rivets 29. The cap 26 is also provided with a flange 33 that is of a lesser diameter than the threaded portion, and where the flange and threads meet, a shoulder is formed. Adapted to be removably secured on the flange 33, is a pan 31, the open end of which abuts the shoulder. The screws 32 pass through suitable holes in the pan to engage with threaded holes formed in the flange 33. As shown in Fig. 4, a chamber is thus formed in the cap when the pan is assembled therewith, which chamber is adapted to receive the insulation 25.

Secured to the outer shell 3 at convenient intervals are fillers or supporting blocks 40, shown detached in Fig. 6, which blocks 40 are preferably riveted by vertical rivets 41 to the shell of the outer tank and are preferably not riveted to the inner tank shell, but the inner tank shell preferably rests upon such supporting blocks and is secured in position by other means as follows:

At convenient distances from the longitudinal middle portion of the tank, angular members 42 are riveted to the bottom shell of the inner tank through the legs 43 while the legs 44 depend vertically below the inner tank shell.

Riveted to the inner face of the outer tank shell are angular members 45 whose horizontal legs 46 are riveted to the outer tank shell and whose vertical legs 47 project upwardly approximately in contact with the depending legs 44 of the member 42 and as the members 42 are riveted to the inner tank shell and the members 45 are riveted to the outer tank shell, it will be evident that independent longitudinal movement of the inner tank shell with relation to the outer tank shell is thereby prevented. Such longitudinal movement is likewise prevented by the fact that there is interposed between the convex heads 2 and the concave heads 4 a filler of insulation which is intended to substantially fill the gap between such heads 2 and 4 though it is preferred that the anchor members 42 and 45 shall be of sufficient strength to prevent shifting of the tank.

To secure the tank in position I employ a conventional tank anchor indicated at 60 in Figs. 1 and 2, which tank anchor is provided with flanges 61 extending longitudinally and transversely of the member 60 and through the flanges 61 are extended rivets 62 which pass through the outer tank shell and through the horizontal leg 46 of the members 45 be-

fore referred to, thus securing such tank anchor in position positively to the outer tank shell and due to the contact of the flanges 44 and 47 before referred to anchoring the inner tank in position with reference to the underframe.

As the underframe details form no part of the present invention and the tank forming the subject matter of this application 10 is adapted to be used with various types of underframes, I have indicated the underframe diagrammatically in dot and dash lines in Fig. 1, which dot and dash lines indicate a car sill 70 which may be of any form, and on the sill 70 I have indicated anchor stops 71 adapted to coöperate with the tank anchor 60 to hold the tank in proper position and prevent excessive movement of the tank on the underframe.

20 To permit removal of the outer shell of the tank it is made separable as follows:

Attached to the contiguous edges at the upper side of the body of the tank are sections of what is commonly known as steel 25 sheet piling *a*—*b* one part *a* of a sheet being secured to one tank sheet *a'* and the other part *b* of the sheet being secured to the contiguous sheet *b'*.

The sheet piling is commonly formed with 30 edge portions adapted to interlock with other piling sheets of the same shape, but in the present use of it the piling sheets are cut so that one portion *a* may be attached to the tank sheets and another portion *b* of 35 the same piling sheet may be attached to other tank sheets and when brought together by longitudinal movement of the tank sheets the piling will interlock and thereby connect such tank sheets together.

40 To connect other contiguous edge portions of the outer shell of the tank angles *c*, *d*, are riveted thereto as shown in Fig. 2, and bolts *e* or equivalent securing means are projected through the outstanding legs 45 of such angles.

It is evident that the outer tank shell is thus formed so as to be separable when desired, one manner of causing such separation being to remove the rivets or bolts connecting the concave heads to the sheets of 50 such outer tank shell.

One of the objects of removing the outer tank shell is to permit the inspection and repair of the insulation and the inner tank shell, and more frequently than otherwise it is not necessary to remove the entire outer shell. The usual inspection will require 55 nothing more than the removal of bolts *e*, disconnecting the tank angles *c* and *d*, and 60 the rivets or bolts connecting sheets *a'* with the concave heads 4, whereupon the tank sheets *a'* will be pivotally suspended from the interlocking sheet piling sections *a* and *b*. Tank sheets *a'* may then be swung outwardly and upwardly, such displacement of

said tank sheets exposing to view a large area of the insulation, which may be repaired or replaced if necessary.

Should there be any leakage in the upper part of the inner tank, the seepage of liquid therefrom will find its way through the joints of the insulation to the exterior thereof, and cause a plainly discernible ferrous discoloration. The upper portion of the outer tank shell comprising the outer dome and outer tank sheets *a'* and *b'* may be lifted as an integer, by a crane or other hoisting means, after the rivets or bolts connecting outer tank sheets *b'* and the concave heads 4 have been removed. The repair of the upper part of the inner tank shell may then be made, or the contiguous insulation may be inspected, replaced or mended.

Often, the bottom of the inner tank consists of a single metallic sheet as shown in Fig. 1, and, in such case, there is little or no danger of repairs being needed in this portion of said tank, but, where exceptions occur, dome cap 26 may be removed and a short beam be inserted into the interior of the inner tank shell. Such beam is then turned to a horizontal position to more than space the dome opening in the inner tank shell, and the chains or cables of a crane or hoist are then passed through the dome and attached to or about said beam. A winding up of the chains or cables will then lift the inner tank shell and all the insulation covering the same away from the car underframe and the bottom sheet of the outer tank shell.

The upper part of the outer tank shell having been removed, all of the insulation is exposed and the entire inner tank shell is readily accessible.

105 The insulated tank here illustrated is designed to hold volatile inflammable products having a vapor tension of over 10 lbs. per square inch at a temperature of 100 degrees Fahrenheit. Therefore, the dome cap 26 is not only screwed into pan 28, but is locked against withdrawal by means, best shown in Fig. 1, 3 and 10.

In said figures, a vent pipe 75 extends from the interior of the inner tank shell 1 through and above the dome head 21 of the outer tank shell, having a cock or other valve 80 attached to its upper end. A discharge pipe 76 is positioned on the opposite side of pan 28, preferably diametrically opposite vent pipe 75, and also projects above dome head 21 of the outer shell and downwardly to the bottom of the interior of inner tank shell 1, where it is held by a clamping device 77, seen best in Fig. 1.

115 120 125 A closing cap 78 is screwed or otherwise secured to the upper end of discharge pipe 76 and has spaced outstanding lugs carrying a pivot pin. One end of a locking bar 79 is pivoted to said pin and extends across

the top of dome cap 26, bearing against an upward extension thereof. The outer end of locking bar 79 is bifurcated to pass downwardly over cock 80, a handle 81 of which is placed in a vertical position to permit the passage of locking bar 79, after which cock handle 81 is turned horizontally to lock the locking bar 79 in dome cap-retaining position.

10 Assuming a condition wherein the lading has established a relatively high vapor tension within inner tank shell 1, and desiring to remove dome cap 26, it is first necessary to turn cock handle 81 to vertical position, 15 when locking bar 79 may be swung out of the path of withdrawal of dome cap 26. But such turning of cock handle 81 opens cock 80, allowing a rapid exhaust of the vapor creating the tension in the inner tank shell 1. By the time dome cap 26 has been unscrewed the vapor tension has been dissipated, removing the otherwise present danger of the dome cap being blown into the face of the trainman or laborer removing it.

10 The discharge of the fluid lading in inner tank shell 1 is accomplished by making an air hose connection to cock 80 and opening the latter, it being necessary to release locking bar 79, and, using it as a handle, unscrew discharge pipe cap 78. Pneumatic pressure being caused to pass through vent pipe 75 forces the fluid lading to pass up through discharge pipe 76, to the upper end of which a hose is usually connected to convey the lading to any desired receptacle.

15 Figs. 11 and 12 show a modified dome cap-locking means, the vent and discharge pipes 75 and 76, respectively, being on the same side of pan 28. Locking bar 79^a extends partly over dome cap 26, the latter being provided with upstanding lugs 82, which are adapted to engage said locking bar upon a slight rotary movement of dome cap 26, and to so prevent its further turning. Opposite cock handle 81^a, locking bar 79^a is bent to clear said handle, which, when in its valve-closing position, extends over a part of said bent portion of locking bar 79^a 20 and prevents it from being swung to a dome cap-releasing position without opening cock 80^a.

25 Discharge of the lading is brought about in the manner already described in connection with the other dome cap-locking means.

What I claim is:

1. In combination in an insulated tank, an inner tank shell, insulation about the exterior thereof and an outer tank shell covering the said insulation and comprising tank heads, spaced sections extending between and rigidly combined with the same and removable sections.

65 2. In combination in an insulated tank,

an inner tank shell, insulation applied to the exterior thereof and an outer tank shell comprising shell portions some being maintained spaced by means other than similar portions, other portions having a hinge connection with the first mentioned portions and being adapted to be disconnected and swung away from said insulation.

3. In combination in an insulated tank, an inner tank shell, insulation applied to the exterior thereof, an outer tank shell comprising vertically spaced top and bottom sections, tank heads connecting the same and side sections, hinge connections between the top and side sections and a locking connection between the side and bottom sections adapted to be unlocked.

4. In combination in an insulated tank, an inner tank shell, insulation applied to the exterior thereof, an outer tank shell comprising vertically spaced sections, side sections and tank heads, means connecting the latter to the various sections, and hinge and locking connections between the side sections and the vertically spaced sections, some of said section-connecting means being adapted to be removed to permit removal and displacement of various sections.

5. In an insulated tank which comprises inner and outer shells provided with telescoping domes having apertured heads, a pan-shaped member connecting said heads and forming a passage between the apertures therein to the interior of the inner shell, an insulated closing-cap for said passage, and insulation interposed between said tank shells and said domes.

6. An insulated tank comprising inner and outer shells, insulation between said shells, said outer shell being formed of separate sections, hinge joints connecting some of the sections and means securing some of said sections adapted to place said hinge joints under tension.

7. An insulated tank comprising inner and outer shells, insulation between said shells, said outer shell being formed of separate longitudinal sections including a bottom section, and means secured to said inner shell and the bottom section of said outer shell for preventing relative movement of said shells.

8. In a tank car, an insulated tank comprising inner and outer shells, said outer shell being composed of separate sections hingedly and detachably connected together, and spaced from the inner shell, insulation between said shells, dished heads for the shells, insulation between said heads, means for connecting said separate sections together, and means for anchoring said shells against relative movement.

9. An insulated tank for tank cars comprising an inner shell having convex ends and an outer shell having concave ends, insu-

- lation secured to the convex surfaces of said ends, insulation between said shells, said outer shell comprising a plurality of separate sections forming the upper and lower portions of said shell and removably connected together, means connecting said sections and means for connecting the shells against relative movement.
10. An insulated tank for tank cars comprising spaced shells, insulation between the shells, heads for each of the shells, insulation between the heads, one of said shells comprising interlocking sections adapted to have a relative swinging movement, means for detachably uniting the sections of said shell and means for preventing relative movement of said shells.
11. In combination, an insulated tank for a tank car, said tank comprising an inner shell with convex ends and an outer shell with concave ends opposing said convex ends, insulation between the shells and the ends, said outer shell being composed of a plurality of separate and detachably connected sections, and means for connecting said sections.
12. In combination, an insulated tank comprising inner and outer shells, said outer shell being composed of a plurality of separate sections detachably connected together, certain of which are removable substantially independently of the others, insulation between the shells, and an anchor for said inner shell comprising angles secured, respectively, to each of said shells.
13. An insulated tank comprising an inner shell having a dome and dished ends, insulation surrounding the shell, the dome and covering the ends, a plurality of detachably and removably connected sections adapted to surround said inner shell and its insulation and form an outer shell, insulated ends for said outer shell, a dome for the outer shell adapted to inclose the dome of the inner shell, a flanged, screw-threaded pan-like member for connecting the domes together and affording a passage way leading to the interior of the inner shell, an insulated cap for closing said passage way, means for detachably connecting the sections and adapting them to be separated, and means for interconnecting the shells together.
14. In combination, an insulated tank comprising inner and outer shells, an insulating filler interposed between said shells, said outer shell being composed of separable plate sections, certain of which are hingedly connected together, a plurality of rigid supports for the inner shell resting on the outer shell, and an inner shell anchor comprising parts connected to each shell.
15. An insulated tank comprising an inner shell provided with convex ends and an apertured dome, an outer shell composed of sections separable longitudinally and provided with concave ends and an apertured dome, certain of said sections being hingedly connected to adjacent sections, and other sections being detachably connected together, said outer shell, dome and ends being spaced from said inner shell, an insulating medium interposed between and in contact with said shells, and means connecting said shells to prevent relative movement therebetween.
16. An insulated tank comprising an inner shell, an outer shell spaced therefrom and comprising separate sections detachably secured together, insulation between said shells, interlocking connections between some of the sections and overlapping connections between some of the sections adapted to place said interlocking connections under strain.
17. An insulated tank comprising inner and outer metallic shells, insulation interposed between said shells, said outer shell being composed of a plurality of separable sections, certain of which have a hinged connection with adjacent sections, and means for detachably connecting other sections to place all of said sections under tension and for bringing the outer shell into contact with the insulation.
18. An insulated tank comprising a plurality of metallic shells spaced from each other, one of said shells being composed of separate sections detachably connected together to permit the removal of certain sections, insulation interposed between said shells, and means for connecting the shells against independent movement.
19. In a tank car, an underframe, an insulated tank comprising inner and outer shells, insulation between said shells, said outer shell being composed of separably connected sections, and internal anchoring means preventing substantial movement between the shells.
20. In an insulated tank comprising inner and outer shells, insulation interposed between the shells, means for connecting the shells, spaced means acting to prevent longitudinal movement of said shells, said outer shell being composed of sections separable on different longitudinal lines.

In witness whereof I have hereunto set my hand in the presence of two witnesses.

ALLEN E. OSTRANDER.
